T. A. PEEBLES

APPARATUS FOR REGULATING THE MIXTURE OF GASES

Filed Dec. 24, 1924

UNITED STATES PATENT OFFICE.

THOMAS A. PEEBLES, OF PITTSBURGH, PENNSYLVANIA.

APPARATUS FOR REGULATING THE MIXTURE OF GASES.

Application filed December 24, 1924. Serial No. 757,958.

The invention described herein relates to certain improvements in mechanism for ensuring a sufficient supply of air for the combustion of gases in a furnace. Gases for heating purposes are obtained from coking ovens, blast furnaces, producers, etc. As is well known to those skilled in the art, the pressure of gases from these sources will vary from time to time and frequently the change of pressure will be large and occur suddenly, and means must be provided for adjusting the air supply in accordance with such changes of pressure of the gas. For purposes of description, the normal supply pressure of the gas may be considered as four pounds and the pressure of the air for combustion as about two inches water column or about one and one-half to two ounces. The type of mechanism in general use for controlling the admixture of gas and air for combustion, when the difference between air and gas is not great, consists of two inverted cups having their open ends immersed in a liquid i. e., water or oil, in a tank, the cups being suspended from the ends of a lever so that the movement of one cup will cause an opposite movement of the other. The lever is adapted to control the operation of mechanism for regulating the flow of the gas or air. The areas of the closed ends of the bells are inversely proportional to the normal pressure of air and gas on the bells so that the pressure in one bell will counterbalance that in the other and their relative positions will not change except on a change of pressure in one of the bells. Such a construction cannot be employed where the gas has a pressure greatly in excess of that of the air, as if gas at a pressure considerably above that of the air be introduced into the gas cup of the machine above described, the water within the cup will be forced out and the gas escape and hence when using high gas pressure provision must be made for the formation of liquid column outside of the cup of sufficient height to counterbalance a gas pressure a little greater than the maximum pressure of the gas. If the pressure of gas is four pounds and the cup immersed in water or oil, the cup must be made of such a length that when gas at four pounds is admitted to the cup the column of liquid due to difference between the levels of the water or oil in and outside of the cup will be sufficient to counterbalance the gas pressure. In other

words, when water or oil is employed to seal the cup, the latter must have such a length and be immersed to such a depth that by the pressure of the gas in the cup, a water or oil column about nine feet in height will be formed outside of the cup in order to prevent the escape of gas from the cup.

Many objections have been encountered in the manufacture and use of an apparatus embodying the features above described and the object of the invention described herein is to provide for counterbalancing two differing pressures by liquid columns approximately equal in height and consists in immersing the cups in liquids differing in specific gravity proportional to the difference in pressure of the air and gas. The invention is hereinafter more fully described and claimed.

In the accompanying drawings Figure 1 is a partial sectional view of a regulator constructed in accordance with one form of this invention and Fig. 2 is a diagrammatic view showing the regulator operatively arranged with gas and air supply pipes.

In the practice of the invention, an inverted cup or bell 1 is immersed for a suitable distance in a liquid, as oil or water, the depth of immersion being dependent on the pressure of the air admitted to the interior of the cup or bell through a nozzle 2. This bell is suspended from one end of a lever 3 and from the opposite end of said lever is suspended a bell or inverted cup 4, the parts being so arranged that the bell 4 will be immersed in a liquid contained in a chamber 5 the gas being admitted into the bell through a nozzle 6. The areas of the closed ends of the bells are inversely proportioned to the respective normal pressures carried in these bells. It will be readily understood that if the bells or cups were immersed, an equal distance into the same liquid, or two liquids having approximately the same specific gravity and the gas admitted into the bell 4 at a pressure substantially greater than the pressure of the air in the bell 1, the liquid in the bell 4 would be forced out allowing the gas to escape. In machines of this type, movements of the bells as the pressure changes, should be equal and comparatively small, and it would be impracticable to make the bell 4 of sufficient length as to permit of its immersion such a distance as to prevent the liquid being forced out of the bell when the pressure of gas is greater

than that of the air. In order to prevent the blowing out of the liquid as above stated, the bell 4 in which the higher pressure is maintained is immersed in a liquid having a higher specific gravity than that of the liquid in which the air bell is immersed. If this liquid for the gas bell has a specific gravity greater than that of the other liquid in the ratio of the pressures in the air and

10 gas bells, the displacement of the two liquids by the air and gas will form columns of substantially the same height.

As for example, if the bell 1 be immersed in oil and the pressure of air in the bell is

15 two or three ounces, the bell 4 in which a normal gas pressure of four pounds is maintained, the liquid in which the bell 4 is immersed should have a specific gravity greater than that of the other liquid

20 proportional to the relative pressure of the air and gas, so that two columns of a liquid will be normally substantially equal. In the embodiment of the invention set forth herein, the air bell is immersed in either oil

25 or water which do not differ greatly in specific gravity, and the gas bell 4 is immersed in mercury, the specific gravity of which has approximately the same relation to that of the water or oil as the two pressures in the bells.

In the construction shown herein which has been found desirable, the bell or inverted cup is located at one end of a tank 7 containing either oil or water, while the

25 chamber 5 containing mercury, as arranged at the opposite end of the tank, the lever 3 from which the bells are suspended, is secured to a beam arranged transversely of the tank and pivotally supported about mid-

30 way of its length. As previously stated, the areas of the closed ends of the respective bells are nearly proportional to the pressures normally maintained therein so that the bells will be approximately in alinement.

35 The chamber 5 is made of such a length and so arranged within the tank that its open upper end will project far enough above the normal level of the oil or water in the tank, that the displacement of the water

40 or oil in the bell 1 will not raise the water in the tank above the upper end of the chamber. It is preferred that the chamber 5 and the nozzle 6 should be integrally connected at their lower ends. The gas pipe 8 is connected by suitable means to the lower end of the nozzle which projects upwardly in the chamber a substantial distance above the maximum level attained by the mercury, by reason of its displacement from the bell.

45 As the changes in pressure of the gas are considerable and occur suddenly, provision should be made for sudden and extreme movements of the bell 4. Suitable means to that end consist of an inverted cup or bell

50 9 enclosing the chamber 5 and movable with

the bell 4. The bell 9 is preferably similar to the bell 1 so as to act as a counterbalance for the latter. As the bell 9 is immersed in the liquid contained in the tank, movements of the bells 4 and 9 due to changes of gas pressure in the bell 4 will be resisted by changes of pressure in the bell 9, and hence the bells 1 and 4 will not move distances proportional to changes of pressure in the bell 4. In order to ensure proper movements of the bells, the bell 9 is provided with a pet cock 10 whereby the flow of air into and from the bell 9 can be regulated, thereby insuring gradual movements of the bells. In order to effectively transmit the movements of the bells to means controlling the flow of air, the lever 3 is connected to a motor mechanism preferably constructed as shown whereby incremental movements of the air controlling mechanism is ensured.

While any suitable form or construction of mechanism may be employed for connecting the lever 3 to mechanisms controlling the flow of gas and air to the point of mixing, it is preferred to employ the construction shown herein.

The regulating mechanism herein illustrated for shifting the valves in the fluid lines for the purpose of varying the pressure of one or the other, or both, of said fluids may be replaced by any suitable regulating mechanism capable of responding to the movements of a lever such as the lever 3. Such a regulating apparatus has been illustrated and described by me in my Patent No. 1,338,956 of May 4, 1920, and consequently, I have avoided anything but a more or less general description in this application, since it will be understood that the regulator functions in substantially the same way as the one disclosed in the patent and controls the valve or similar mechanism in the manner disclosed by the patent.

The lever 3 is connected by a rod 11 to an arm 12 pivotally supported at 13. On this arm is pivotally mounted a bell crank lever having an arm 14 connected to the valve stem 15 of the pilot valve mechanism 16 while the other arm 17 of the bell crank lever is connected by a link 18 to a swinging post 19. On a change of pressure in either of the bells 1 or 4, the arm 12 will be shifted up or down, carrying with it the bell crank lever whereby the motion will be transmitted through the stem 15 to the movable member of the valve mechanism 16. This valve mechanism is connected in a suitable manner to opposite ends of the cylinder 20. By the admission of fluid pressure the piston of said cylinder will be moved up or down and as such piston is connected by a rod 21 to the frame 22, the latter will also be shifted. This frame is connected as shown to the stem of the valve mechanism controlling the flow of gas or

air and the latter will be shifted towards open or closed position. In order to limit the movement of the frame 22 a compensating mechanism is employed. This compensating mechanism consists of the swinging post 19 which is connected as hereinbefore described, by a link 18 to the bell crank lever, and has pivoted thereto an angularly arranged bar 23. This bar is adapted to slide along a shoe 24 secured to the frame 12. In practice this bar has been adjusted at an angle to the axis of the cylinder dependent upon the incremental movements desired to be imparted to the piston and frame. As the frame moves upward, the shoe will slide along the angularly arranged bar and thereby shift the swinging post to the right or left. By the movement of this post, the bell crank lever will be correspondingly shifted and the valve mechanism in the pilot valve will be moved to a reverse position, i. e., towards closed position, from that imparted to it by the movement of the bells.

25 While the invention has been described in connection with the formation of a combustible mixture of gas and air, it will be understood that the apparatus can be employed in forming a mixture of any two gaseous elements.

I claim herein as my invention:

1. Apparatus for regulating the delivery of one fluid in response to relative variations between the pressure of that and another fluid maintained at a substantially different pressure, comprising a pivoted lever, inverted bells secured to said lever on opposite sides of the pivot point thereof, connections for admitting one fluid pressure to the interior of one bell and the other fluid pressure to the interior of the other bell, said bells being so proportioned as to effective area exposed to the fluid pressure therein contained that their effective areas are approximately inversely proportional to the pressures of the two fluid pressures acting on the respective bells, a liquid seal for the bell, to which the lower fluid pressure is delivered, and a liquid seal for the other bell, the liquids of said seals being respectively such that their specific gravities are approximately proportional to the pressures of the respective fluid, and means actuated by the tilting of said lever for controlling the pressure of one of said fluids.

2. Apparatus for regulating the pressure of a fluid, comprising two counteracting inverted bells, each exposed to a separate fluid under pressure, the effective areas of said bells being approximately inversely proportional to the pressures of the fluids acting on the respective bells, a separate liquid seal for the lower edge of each bell, the liquid of each seal being such that the specific gravities of the liquids of the seals of the

respective bells are approximately directly proportional to the fluid pressures acting on the respective bells, and means actuated by the movement of said bells in response to a variation in one or the other fluid pressure for controlling the variation of pressure of one of said fluids.

3. Apparatus for regulating the pressure of a fluid, comprising two counteracting inverted bells, a separate liquid seal for each bell, and one bell being substantially smaller than the other, an inverted bell inclosing the smaller, moving with both said bells, and projecting into the liquid of the seal of the larger bell, and having a restricted port formed therein above the level of said liquid, and means actuated by the movement of said bells for controlling the pressure of the fluid delivered to one of the bells.

4. Apparatus for regulating the pressure of a fluid, comprising two counteracting inverted bells, a separate liquid for sealing the edge of each bell, one bell being substantially smaller than the other, a third bell of substantially the same size as the larger of said bells and having its edge sealed by the sealing liquid of the larger bell, and having an adjustable port formed therein above the level of the sealing liquid, a pivoted lever on which all of said bells are mounted, and means actuated by said lever for controlling the pressure of the fluid delivered to one of said bells.

5. Apparatus for regulating the delivery of one of the components of a combustible mixture of gas and air where the gas is maintained at a pressure substantially higher than the air, which comprises two counteracting, connected, inverted bells, each projecting into a separate liquid forming a liquid seal, the specific gravity of said liquids being approximately directly proportional to the normal pressures of the gas and air, means for introducing air under pressure into the bell sealed by the lighter of said liquids, means for introducing the gas under pressure into the bell sealed by the heavier of the two liquids, and means responsive to the movement of the bells occasioned by a variation in the pressure of the gas or air for controlling the delivery of one of the two fluids at the point of their mixture.

6. Apparatus for regulating the delivery of one of the components of a combustible mixture of gas and air where the gaseous fluids constituting said mixture are maintained at substantially different pressures, which comprises two counteracting, connected, inverted bells, each projecting into a separate liquid forming a liquid seal for the edge of the associated bell, the specific gravities of said liquids being substantially directly proportional to the pressures of the components of the combustible mixture, means for

introducing into the bell sealed by the lighter of the two liquids a fluid pressure corresponding to the pressure of the low-pressure component, means for introducing into the other bell a pressure corresponding to the pressure of the high-pressure component, the effective areas of said bells being inversely proportional to the pressures therein normally contained, and means ac- tuated by the movement of the bells in response to variations in the pressures therein contained for controlling the delivery of one of said components at the point of mixture. 10

In testimony whereof, I have hereunto set my hand.

THOMAS A. PEEBLES.
